UNITED STATES PATENT OFFICE.

WILLIAM H. H. STINEMAN, OF BALTIMORE, MARYLAND, ASSIGNOR OF ONE-THIRD TO
ARTHUR WEGEFARTH, OF BALTIMORE, MARYLAND.

STOKER.

1,032,164.

Specification of Letters Patent.

Patented July 9, 1912.

Application filed February 12, 1912. Serial No. 677,188.

To all whom it may concern:

Be it known that I, WILLIAM H. H. STINEMAN, a citizen of the United States, residing at Baltimore, in the State of Maryland, have 5 invented certain new and useful Improvements in Stokers, of which the following is a specification.

My invention relates to improvements in stokers and especially to that class in which the fuel is fed from the bottom of the furnace to the under side of the fire. In this class of devices the greatest efficiency and extent of fire surface are obtained, by providing a graduated fuel conveyer, by means 15 of which a portion of the fuel will be forced out of the magazine throughout its entire length, so that an equal distribution of the fuel will be accomplished. By graduating the feed device along the length of the fire-box in the direction of the feed, the fuel will be distributed and deposited along the 20 length of the fire-box under the fire in even quantities to maintain a uniform supply throughout the area thereof.

25 The object of the invention is to provide a graduated conveyer to reduce the carrying capacity thereof toward the rear of the fire-box, and to decrease the spaces between the flights of the conveyer toward the rear end 30 thereof, thereby increasing the lifting capacity of the graduated flights, whereby a uniform distribution of the fuel in the fire-box will be maintained. And further to provide a graduated magazine, or magazines, 35 each having a uniform outlet to the fire-box and spiral shaped grooves or corrugations beginning near one side of said outlet and increasing in depth and terminating at the opposite side of the said outlet, 40 the width of said grooves or corrugations decrease toward the rear end of the magazines to correspond to the decreased spaces between the flights of the conveyer, whereby a large portion of the fuel between each 45 flight of the conveyer will be held in said grooves or corrugations and carried, or lifted up, through the outlet of the magazine to the fire-box, thus preventing choking of the said conveyers and greatly reducing 50 the power necessary to operate same. Also to provide means near the front end of the conveyers to cut off, entirely, or partly, the travel of the fuel toward the rear end of the conveyers, whereby the fuel will be forced

up more freely at the front end of the fire 55 box when desired.

My invention consists of the novel construction and arrangement of the parts and combination of parts hereinafter more fully set forth in the following specification and 60 pointed out in detail in the claims.

In the accompanying drawings,—Figure 1 is a vertical sectional view of a locomotive and tender with my invention applied thereto. Fig. 2 is a plan view of the fire-box, 65 showing my invention applied thereto. Fig. 3 is a front view of Fig. 2. Fig. 4 is a vertical sectional view of one of the magazines and conveyers on the line X—X of Fig. 1. Fig. 5 is a similar view to Fig. 2, 70 with the fire-grate removed. Fig. 6 is an enlarged detailed plan view, partly broken away, of the lower section of one of the magazines showing the spiral grooves or corrugations. Fig. 7 is an inverted plan 75 view, partly broken away, of the upper section of one of the magazines, also showing the spiral grooves or corrugations. Fig. 8 is a detail rear view of the cut-offs and their connecting rod for operating same. 80

Referring to the accompanying drawings, forming part of this specification, and in which like reference numerals designate like parts throughout the several views thereof, 1 designates a cylindrical cone-shaped magazine 85 projecting through the front wall of the furnace and supported at its rear end by the support 2. In the present instance two magazines and conveyers are employed, both of which are identical in construction 90 and operation, and shown applied to a locomotive. These magazines 1 are constructed of two sections bolted together at 3; the upper section being provided with a uniform outlet 4 having a channel 5 extending 95 around the entire upper edge thereof, and into which the fire-bricks 6 are fitted. The grate 7 has its upper surface flush with the upper surface of the channel 5. It will be seen that by having the channel 5 around 100 the entire edge of the outlet 4, it is not necessary to fasten the bricks 6 in place and they can readily be removed and new ones inserted when desired. These magazines 1 are also provided with spiral grooves or 105 corrugations 8 which begin at a point near one side of the outlet 4 and gradually increase in depth and terminate in their great-

est depth at the other side of the outlet 4. The grooves or corrugations 8 decrease in width toward the rear end of the magazines, the purpose of which will be hereinafter set forth.

The conveyers 9 have their front ends journaled in the wall of the hopper 10 and are straight or uniform in size back to the inner surface of the fire-box, at which point they begin to taper to the rear end thereof, resting in and conforming to the cone shape of magazines 1, thus reducing the carrying capacity toward the rear of the fire-box. The flights of the conveyer not only decrease in size, but the spaces between the flights decrease toward the rear thereof to conform to the width of the grooves or corrugations 8, whereby the conveyers are given greater lifting power and a uniform feeding of the fuel to the fire-box is obtained. The tendency of a screw conveyer is to carry the fuel to the rear of the fire-box and to choke the conveyer. The grooves or corrugations 8 will prevent the choking of the conveyer by holding a greater portion of the fuel therein while the conveyer forces it up and discharges it through the outlet 4 to the fire-box, thus preventing too much of the fuel from being carried to the rear of the magazine and choking the conveyer, thereby greatly reducing the power necessary to operate the said conveyers. These grooves or corrugations 8 are spiral shaped to correspond to the spiral shape of the flights of the conveyer, and increase in depth toward their discharge ends, or in the direction of the revolution of the conveyer, thereby increasing the space on the discharge side of the conveyer, thus preventing choking of the conveyers and assuring a free discharge of the fuel to the fire-box.

At the front of the magazines 1 is arranged a hopper 10 communicating therewith, and having a neck 11 into which the fuel front ends of the conveyers extend, the said hopper 10 being slightly flared at its mouth. This hopper 10 in the present instance is just under the fireman's deck 12. The fuel is fed from the tender 13 to the hopper 10 by means of the conveyers 14 and 15, the former being under the fireman's deck and the latter on the tender 13. From the hopper 10 the fuel is carried into the magazines 1 by the conveyers 9 and forced up through the outlet 4 to the fire-box uniformly throughout its entire length. In the bottom of the hopper 10 are two plungers 16 which are operated in and out between the flights of the conveyers and hold the fuel against any backward movement and cause it to move forward in the magazines. These plungers 16 are operated by the levers 17 connected to one end thereof and journaled in the bearing 18 and having their other ends pivoted to one end of the eccentric rods

19, which latter are mounted on the gear wheels 20, which latter are fast on the ends of the conveyers 1, 1'. At the front ends of the magazines 1 are cut-offs 21 adapted to operate in and out of the magazines between the flights of the conveyers to cut off entirely, or partly, the travel of the fuel toward the rear of the magazines and cause it to feed up through the outlet at the front of the fire-box when it is desired to feed the fuel more freely at this point. These cut-offs 21 are journaled in the bearings 22 on the outside of the magazines and have their lower ends connected by the links 23 to a rock shaft 24, which latter are connected to one end of the eccentric rods 19. The movement, or rather the stroke, of the cut-offs can be regulated by the lever 25 to change the position of the shaft 24 on the eccentric rod 19.

The power shaft 26 is provided with the worms 27, 27 which mesh with the gear wheels 20 on the outer ends of the conveyers 9, by means of which the latter are operated. The power shaft 26 is also provided with a worm 28 in mesh with the gear-wheel 29, which latter is mounted on the end of the shaft 30. This shaft 30 is provided with a sprocket-wheel 31 on one end connected by the chain 32 to the sprocket 33 on the outer end of the conveyer 14 by means of which the latter is operated. The shaft 30 is connected to a shaft on the tender by means of a double universal joint 34. This shaft on the tender is composed of two sections 35 and 36 connected by a sleeve 37 in which the ends of the said sections 35 and 36 are free to move longitudinally. The universal joint 34 permits of any movement of the engine and tender without interfering with the revolution of said shaft. On one end of the shaft 36 is a sprocket wheel 38 connected by a chain 39 to a sprocket 40 on the end of the conveyer 15. This latter conveyer 15 tapers, or increases in size, toward the discharge end thereof to prevent choking of the conveyer.

The operation of the device is as follows: The fuel being loaded into the tender 13, and the power shaft 26 started, the fuel will be carried by the conveyer 15 to the conveyer 14 and from thence to the hopper 10, from which latter point it feeds to the two magazines 1, 1, and is carried by the conveyers 9, 9 back into the magazines and fed through the outlets 4, 4, to the fire-box as heretofore described.

While I have shown and described my invention applied to a locomotive, it is obvious the same is applicable to any type of furnace.

Having thus described my invention, what I claim is:

1. In an underfeed furnace, the combination of a fire-box provided with a fuel sup-

- port, a magazine within said fire-box having a discharge outlet at the top thereof, and spiral grooves or corrugations beginning near one side of said outlet and extending around and increasing in depth to the opposite side of said outlet, and a screw conveyer within said magazine adapted to be revolved in the direction of the increase of depth of the said grooves or corrugations. 5
- 10 2. In an underfeed furnace, the combination of a fire-box provided with a fuel support, a magazine within said fire-box having a discharge outlet to the fire-box, and spiral grooves or corrugations beginning near one side of said outlet and extending around and increasing in depth to the opposite side of said outlet, a hopper having communication with said magazine, a screw conveyer within said magazine and projecting 15 into said hopper, adapted to be revolved in the direction of the increase of depth of the said grooves or corrugations, and means for operating said conveyer. 20
3. In an underfeed furnace, the combination of a fire-box provided with a fuel support, a magazine within said fire-box having a discharge outlet to the fire-box, and spiral grooves or corrugations beginning near one side of said outlet and extending around 25 and increasing in depth to the opposite side of said outlet, each successive groove or corrugation decreasing in width toward the rear of said magazine, and a screw conveyer within said magazine, the flights of which 30 decrease in size toward the rear end thereof, said conveyer being adapted to be revolved in the direction of the increase of depth of the said grooves or corrugations, and the 35 spaces between the successive flights decrease toward the rear end of said conveyer to correspond to the decreased width of the said grooves or corrugations. 40
4. In an underfeed furnace, the combination of a fire-box provided with a fuel support, a magazine within said fire-box having a discharge outlet at the top thereof, and spiral grooves or corrugations beginning near one side of said outlet and extending around and increasing in depth to the opposite side of said outlet, a screw conveyer within said magazine, adapted to be revolved in the direction of the increase of depth of the said grooves or corrugations, 45 a plurality of cut-offs near one end of said magazine and adapted to be operated in and out between the flights of said conveyer. 50
5. In an underfeed furnace, the combination of a fire-box provided with a fuel support, a magazine within said fire-box having 55
- a discharge outlet at the top thereof, and spiral grooves or corrugations beginning near one side of said outlet and extending around and increasing in depth to the opposite side of said outlet, a screw conveyer within said magazine, adapted to be revolved in the direction of the increase of depth of the said grooves or corrugations, a plurality of cut-offs near one end of said magazine and adapted to be operated in and out between the flights of said conveyer. 60
6. In an underfeed furnace, the combination of a fire-box provided with a fuel support, a plurality of magazines within said fire-box each having a discharge outlet to the fire-box, and each magazine having spiral grooves or corrugations beginning near one side of said discharge outlet and increasing in depth and terminating in their greatest depth at the opposite side of said outlet, a screw conveyer in each of said magazines adapted to be revolved in the direction of the increase of depth of the said grooves or corrugations, a hopper having communication with said magazines, and means for operating said conveyers. 65
7. In an underfeed furnace, the combination of a fire-box provided with a fuel support, a plurality of magazines within said fire-box each having a discharge outlet to the fire-box, and each magazine having spiral grooves or corrugations beginning near one side of said discharge outlet and increasing in depth and terminating in their greatest depth at the opposite side of said outlet, each successive groove or corrugation decreasing in width toward the rear of said magazine, a screw conveyer in each of said magazines the flights of which decrease in size toward the rear end thereof, and the space between each successive flight of the conveyer decreases toward the rear end thereof to correspond with the said grooves or corrugations, said conveyers being adapted to be revolved in the direction of the increase of depth of the said grooves or corrugations. 70
8. In testimony whereof I affix my signature in presence of two witnesses. 75
